BANDAGE WINDING MACHINE

Frank H. Washburn, Jr., Worcester, Mass.

Application July 29, 1938, Serial No. 221,924

17 Claims. (Cl. 91—30)

This invention relates to machines for winding surgical bandages and for simultaneously loading the bandage fabric, usually crinoline, with a substantial application of plaster of Paris powder or other finely divided material.

It is the general object of my invention to provide an improved winding machine for such purposes, and particularly to provide a machine in which the travel of the fabric and of the applied powder is continuously downward.

Other features of my invention relate to the provision of improved feeding and agitating devices for the powder, to the provision of improved means for controlling the winding speed, to the provision of improved electrical operating mechanism, and to the provision of improved means for measuring the bandage and stopping the machine at a predetermined length.

My invention further relates to arrangements and combinations of parts which will be hereinafter described and more particularly pointed out in the appended claims.

A preferred form of the invention is shown in the drawings, in which:

Fig. 1 is a front elevation of my improved machine;

Figs. 2 and 3 are side elevations thereof, looking in the directions of the arrows 2 and 3 in Fig. 1 respectively;

Fig. 4 is an enlarged partial sectional elevation, taken along the line 4—4 in Fig. 1;

Fig. 5 is a side elevation of certain parts shown in Fig. 3 but in a different position;

Fig. 6 is a detail sectional view, taken along the line 6—6 in Fig. 5;

Fig. 7 is a detail side view, looking in the direction of the arrow 7 in Fig. 6;

Fig. 8 is a partial sectional plan view, taken along the line 8—8 in Fig. 2;

Figs. 9 and 10 are detail sectional elevations, taken along the lines 9—9 and 10—10 in Fig. 8 respectively;

Figs. 11, 12 and 13 are detail sectional plan views, taken along the lines 11—11, 12—12 and 13—13 in Fig. 2 respectively;

Fig. 14 is a detail section of a portion of the bandage material;

Fig. 15 is an end elevation of a partially wound bandage;

Fig. 16 is a detail elevation of a doctor blade; and

Fig. 17 is an end elevation, looking in the direction of the arrow 17 in Fig. 16.

Referring to Figs. 1 to 3, I have shown my improved winding machine as mounted in a

casing comprising a back 20, sides 21 and 22, a top 23, a bottom 24 and an upright partition 25 forming a support for many parts.

The operating mechanism is mounted largely on the back 20 and partition 25, but the driving motor M is pivotally suspended from the top 23 by a clamping structure 27 (Fig. 2) enclosing the motor M and pivotally mounted on a cross rod 28 supported by brackets 29 secured to the under side of the top 23.

The motor M is provided with an armature shaft 30 (Fig. 1) having a friction roll 32 adapted to engage and drive a wheel 33 when released for engagement therewith, driving pressure being produced by a tension spring 34.

The roll R of crinoline or other fabric C is supplied on a fibre sleeve 36 (Figs. 2 and 4) which is slipped over a slightly tapered tubular member 37 (Fig. 1), which member is rotatably mounted on a rod 38 fixed in the upright partition 25.

A ratchet wheel 39 (Fig. 7) is secured to one end of the tubular member 37 and is engaged by a latch 40, pivoted at 41 on the partition 25. The latch 40 normally prevents rotation of the wheel 39 and roll R in a clockwise or unwinding direction, as viewed in Figs. 2 and 7.

A hand release lever 42 (Fig. 2) is pivoted at 43 on the partition 25 and is provided with a tension spring 44, normally holding the release lever in inoperative position and against a stop pin 45. The upper end of the release lever 42 underlies the outer end of the latch 40, as shown in Fig. 7. When the lever 42 is moved manually anti-clockwise against the tension of the spring 44, the latch 40 will release the ratchet wheel 39 and the roll R may be unwound to a desired extent for threading or other purposes.

The latch 40 is also provided with a slot 47 (Fig. 7) to receive the reduced end 48 (Fig. 6) of a lever 49, pivoted at 50 in an opening 51 in the partition 25. The outer end of the lever has a deep notch 52 in its upper edge and is yieldingly drawn upward by a tension spring 53. The tension of the spring 53 acts to press the latch 40 against the ratchet 39. The devices for releasing the latch 40 during a winding operation will be hereinafter described.

The cloth C is drawn downward by a winding spindle 55 (Fig. 4) and passes between a glass plate 56 and a metal plate 57, the latter forming the rear part of a hopper H supplying the plaster of Paris or other powdered material.

The cloth C in its downward course passes behind a wiping roll 60 and behind a guide-roll 61,

from which latter roll it is delivered to the winding spindle 55. A guide and presser plate 62 (Fig. 4) is pivoted at 63 to the back 20 and is pressed yieldingly against the roll R' of bandage 5 on the spindle 55 by a light spring 64. The plate 62 presses lightly against the roll R' as it is wound and acts to prevent detachment of the powder from the cloth.

The spindle 55 is shown as transversely slotted 10 to receive the end of the bandage, and is rotatably mounted in a bearing 65 (Fig. 1) secured to the partition 25. Outside of the bearing 65, the spindle 55 is provided with a grooved pulley 66 (Fig. 3) connected by a belt 67 to a small 15 driving pulley 68 secured to and rotatable with the wheel 33 previously described. The wheel 33 and pulley 68 are mounted to rotate together 20 on a stud 70 on the side of the partition 25.

A double-blade agitator 71 (Fig. 11) is mounted 20 to rotate in the lower portion of the hopper H and has a spindle 72 extending through a bearing in the partition 25 and provided with a grooved driving pulley 74 engaged by the belt 67 in its downward run, as indicated in Fig. 3.

25 The agitator 71 assists downward movement of the powder and prevents clogging of the hopper, which might otherwise occur on account of the extreme fineness of the material supplied thereto. One bar of the agitator may be at a 30 greater radial distance from the axis than the other.

The wiping roll 60 (Figs. 4 and 12) extends 35 across the hopper H below the agitator 71 and has an extension 76 (Fig. 12) rotatable in a bearing in the partition 25. A grooved pulley 77 on the extension 76 is engaged by the belt 67 in its downward run. The wiping roll 60 is relatively flat in cross section, as indicated in Fig. 4, and is preferably of the irregular formation shown 40 in Fig. 12 for reasons to be explained.

I also provide an auxiliary hopper H' (Figs. 2 and 4) in which the powder is initially deposited. The hopper H' comprises a bottom plate 80, side plates 81, an end plate 82, a curved top plate 83 and brackets 84. When the auxiliary hopper H' is in operative position, the upper edge 45 of the bottom plate 57^a of the hopper H is received between the bottom plate 80 and the brackets 84, so that the auxiliary hopper is thereby supported for slight angular movement.

A cross rod 86 (Fig. 1) extends through the partition 25 and is pivotally secured at 87 (Fig. 4) to the under side of the hopper bottom plate 57^a. The inner end of the rod 86 is bent to 55 provide an offset portion 88 which extends loosely through an opening in the bottom plate 57^a and engages the lower end of the bottom plate 80 of the auxiliary hopper H'.

At its outer end, the rod 86 (Fig. 3) is provided 60 with an arm 89 extending downward into the path of cam blocks 90 on the winding pulley 66. The auxiliary hopper H' is thus slightly agitated twice during each revolution of the winding spindle, which assists regular down feed of 65 the powdered material.

The guide-roll 61 (Figs. 1 and 13) is mounted 70 in brackets 92 on a doctor bar 93 (Figs. 4 and 16), the upper edge of which is hinged to the lower edge of the hopper bottom plate 57^a. The inward position of the doctor bar 93 is determined by stop screws 95 (Fig. 1) in the bar 93, and a lock lever 96 is provided for holding the bar in operative position. When the bar is unlocked, the bar and roll may be swung outward to the 75 dotted line position shown in Fig. 4 to permit

convenient dumping or clearing of the hopper and the starting of a new roll of bandage.

The doctor bar 93 is provided with a beveled edge 97 (Fig. 17) and with a transverse groove 98, and is also provided with two or more spaced 5 notches 99 in the beveled edge 97, the purpose of which will be hereinafter described. The guide-roll 61 (Fig. 13) is provided with the same number of grooves 100, so spaced and positioned as to be associated with the notches 99 in the operation of the machine.

A knife is provided for conveniently severing the fabric as full rolls are wound on the spindle 55. This knife comprises a fixed blade 105 (Fig. 4) mounted in the back 22 of the casing above a 15 recess 106, and a movable blade 107 extending through a slot 108 (Fig. 2) in the partition 25 and pivoted at 109 to a block 111 (Fig. 1) on the back 20. When a bandage is fully wound, the blade 107 is swung manually in a horizontal 20 plane and cooperates with the fixed blade 105 to cut the fabric.

A measuring roll 112 (Fig. 8), which is commonly of wood with a fabric surface, is pivotally mounted on a stud 113 fixed in the outer end 25 of a bent arm 114 having a pivot stud 115 extending through a bearing 116 in the partition 25.

A spring 118 (Fig. 2) is connected at its lower end to a pin 119 on the arm 114 and at its upper end to a screw 120 adjustable in a fixed 30 bracket 121. The function of the spring 118 is to partially counterbalance the weight of the roll 112 and to regulate the pressure of the roll against the cloth C by which it is frictionally rotated.

Speed control

I will now describe the mechanism which I have provided for rendering the motor operative or inoperative and for controlling the speed of the motor in accordance with the size of the 40 bandage roll R' which is being wound on the winding spindle 55.

A bracket 124 on the motor M (Figs. 1 and 3) projects through an opening 125 in the partition 25 and is engaged by the upper end of a bar 126 which is slidably secured on the partition 25 by screws extending through slots 127 in the bar.

A spring 128 (Fig. 3) normally pulls the slide 50 bar upward against the bracket 124 and is strong enough to overcome the spring 34 (Fig. 1) and swing the motor M so that the roll 32 is spaced from the wheel 33, all as shown in Fig. 1.

A projection 130 on the side of the slide bar 55 124 projects into the notch 52 (Fig. 6) in the latch release lever 49. When the slide bar is raised, the parts assume the position shown in Figs. 6 and 7 and the latch is operative, but when the slide bar is moved downward to start the 60 winding, the latch 49 will be moved clockwise in Fig. 7 to release the ratchet wheel 39.

A link 132 (Figs. 3 and 5) has a pin and slot connection at its upper end to the slide bar 126 and at its lower end is pivoted to a hand lever 65 133 (Fig. 1) extending through and pivoted in the partition 25 and constituting the means by which the operation of the machine is manually controlled.

The lower end 135 (Fig. 1) of the slide bar 70 126 is offset outward and is adapted to be engaged by the hook-shaped upper end of a latch 136 (Fig. 5) pivoted at 137 on the partition 25 and having a laterally extending arm 138 positioned for engagement by a stud 139 in the link 132 75

when the link is moved upward to the position shown in Fig. 3. A spring 140 acts to move the latch 136 to holding position when the latch is released by downward movement of the link.

5 When the operator desires to start the winding, he swings the handle 133 upward, thus moving the link 132 and slide bar 126 downward and allowing the roll 32 to frictionally engage the wheel 33 as shown in Fig. 5. As the downward 10 movement is completed, the bar 125 will be engaged and locked in lowered position by the latch 136.

The motor M will thereafter continuously rotate the winding spindle 55 until the latch 136 is released, either by manual upward movement 15 of the link 132 and pin 139 (Fig. 3) or by automatic means to be described.

For controlling the speed of the motor, I provide a rheostat 145 (Fig. 3) having a plurality 20 of resistance sections numbered from 1 to 10 inclusive and connected in series with a wire 146 leading to one terminal of the motor M.

Separate wires 147 (Fig. 3) also extend from 25 each resistance section to contact plugs 148 (Fig. 25) mounted on a plate 149 (Figs. 8 and 10) of insulating material, which plate is supported on a fixed metal sleeve 150 secured in the partition 25.

A star wheel 152 is mounted on the outer end 30 of a spindle 153 extending through the tube 150 and having a collar 154 mounted on its outer end. The collar 154 has a pin 155 (Fig. 5) projecting therefrom and engaging a shoulder 156 on the latch 136 when rotated clockwise as viewed in 35 Figs. 3 and 5. On such engagement, the latch 136 is pushed back to release the slide bar 126, which thereupon moves upward, swinging the motor M and lifting the roll 32 from the wheel 33.

The star wheel 152 is advanced intermittently 40 by engagement thereof by a pin 160 (Fig. 8) mounted in the side of the measuring roll 112. The pin 160 advances the star wheel 152 one tooth on each revolution of the measuring wheel. The star wheel carries a spring contact 162 (Fig. 45) which engages successive terminal plugs 148 of the rheostat 145 as the star wheel is intermittently advanced.

Electrical connections

50 The electrical connections are shown largely in Fig. 3 and comprise line wires L and L', a wire 170 connecting the line L to one terminal of a switch 171, and a wire 172 connecting the other terminal of the switch to one terminal of the motor M, the other motor terminal being connected to the rheostat 145 by the wire 146 as previously described.

The line wire L' is connected by a wire 174 to the sleeve 150 (Fig. 8) in which the star wheel shaft 153 is mounted. Connection is thus made through the shaft and star wheel to the contact spring 162 and thence to one of the rheostat plugs 148, which plugs are connected through the branch wires 147, the rheostat sections and 65 the wire 146 back to the motor M, thus completing the motor circuit.

When the machine is started to wind a bandage, the contact spring 162 will be on terminal plug 1 so that the rheostat is cut out and the 70 motor operates at its highest speed. At each revolution of the measuring roll 112, the star wheel is engaged by the pin 160 and is moved forward intermittently to successive plugs 148, thus cutting in successive sections of the rheostat. The motor speed is thus reduced one step 75

for each revolution of the measuring roll 112, and the winding speed is kept approximately in inverse ratio to the diameter of the spindle 55.

The last angular movement of the star wheel, by which the latch 136 is released and winding is stopped, also returns the contact spring 162 to the rheostat plug 148 corresponding to section 1, thus resetting the motor for operation at high speed when the winding of a new bandage is started. 10

I consider it desirable that an audible signal should be given once in each revolution of the measuring wheel 112, so that the operator may be advised that winding is proceeding in the desired manner. For this purpose I provide a 15 buzzer 180 (Fig. 3) connected by a wire 181 to the motor connection 172 previously described, and connected by a second wire 182 to the bearing 116 which pivotally supports the arm 114 on which the measuring wheel 112 is mounted. Connection is thus made through the arm to the bearing sleeve 183 of the wheel 112, which sleeve is connected by a short wire 184 (Figs. 4 and 8) to the pin 160 which engages the star wheel 152. 20

Each time the wheel 112 revolves, the buzzer 25 circuit is momentarily closed and a short audible signal is given. As the measuring wheel revolves only by frictional contact with the downwardly traveling fabric, the occurrence of this signal indicates that the fabric is traveling through the 30 machine in the desired manner.

It is desirable that the plaster of Paris or other powder material be as dry as possible when applied to the bandage, and I accordingly provide a heater 190 underlying the auxiliary 35 hopper H' and connected by wires 191 and 192 (Fig. 3) to the terminals of the first and second resistance sections of the rheostat 145. Thus connected, the heater 190 will be operative whenever contact is made with any of the terminal plugs 148 which are numbered from 2 to 10 in Fig. 10, but the heater will be inoperative when contact is made with the plug 148 connected to rheostat section 1. Consequently the heater is in operation during the winding of each 40 bandage but is automatically cut out as the winding is completed. 45

Operation

Having described the details of construction 50 of my improved bandage loading and winding machine, it is believed that the method of operation and advantages thereof will be readily apparent. Briefly stated, the machine is operated as follows:

The auxiliary hopper H' is supplied with plaster of Paris or other powdered material which is fed down into the hopper H by the slight mechanical agitation of the auxiliary hopper from the cam blocks 90 (Fig. 3), assisted if 60 necessary by use of a manual pusher 200 (Fig. 4).

Toward the lower end of the hopper H, the powder is loosened up by the rotating agitator 71 and is carried downward by the cloth C as the cloth is guided against the glass plate 56 by 65 the wiping roll 60 which further agitates the powder. The doctor plate 93 presses a uniform layer of powder against the outer face of the fabric and the double flat portions 60a of the roll 60 press excess powder into the notches 99 70 in the bar 93, the spacing being the same.

The notches 99 cause the excess powder to be deposited in spaced longitudinal ridges on the face of the fabric, as indicated at 202 in Fig. 14. The loaded fabric is then guided verti- 75

cally downward by the roll 61, with the grooves 160 in the roll 61 clearing the longitudinal ridges 202.

As the bandage is thereafter wound on the 5 spindle 55, these ridges tend to separate adjacent layers of the bandage, so that a loosely wound bandage is attained which at the same time is relatively firm and does not easily telescope.

10 My improved bandages, thus wound in spaced layers, are much more accessible to the action of water when desired for use and require very much less time to become effectively moistened, as compared with the usual bandages more tightly rolled.

15 Having thus described my invention and the advantages thereof, I do not wish to be limited to the details herein disclosed, otherwise than as set forth in the claims, but what I claim is:

20 1. A bandage winding machine comprising a winding device, means to rotatably support a roll of fabric, said device and said means being substantially in vertical alignment and substantially spaced apart, means to apply powdered 25 material to said fabric as it is drawn downward by said winding device, and a hopper positioned adjacent the path of vertical movement of said fabric and between said winding device and said supporting means and having a substantial 30 opening in its side wall past which said fabric is drawn downward and at which opening said fabric receives a thick layer of said powdered material.

35 2. A bandage winding machine comprising a winding device, means to rotatably support a roll of fabric, said device and said means being substantially in vertical alignment and substantially spaced apart, and means to apply powdered material to said fabric as it is drawn downward by said winding device, said latter 40 means including a substantially frictionless upright supporting plate, and means to guide said fabric closely adjacent said plate and in sliding contact therewith.

45 3. A bandage winding machine comprising a winding device, means to rotatably support a roll of fabric, said device and said means being substantially in vertical alignment and substantially spaced apart, a substantially frictionless upright supporting plate, means to guide said fabric closely adjacent said plate and in sliding contact therewith, a hopper for powdered material, and means to guide said fabric along said supporting plate adjacent the mouth of said 50 hopper and to press the powdered material against said fabric.

55 4. A bandage winding machine comprising a winding device, means to rotatably support a roll of fabric, said device and said means being substantially in vertical alignment and substantially spaced apart, and means to apply powdered material to said fabric as it is drawn downward, said latter means including a doctor bar having spaced notches in the operative edge 60 thereof, and a guide roller mounted below the edge of said bar and provided with grooves spaced to correspond to the spacing of the notches in said bar.

65 5. A bandage winding machine comprising a winding device, means to rotatably support a roll of fabric, said device and said means being in substantially vertical alignment and substantially spaced apart, and means to apply powdered material to said fabric as it is drawn 70 downward, said latter means comprising a doc-

75 tor bar, a guide roller mounted below the edge of said bar, and a pivoted support for said bar and roller which is swingable from normal position to provide clearance for dumping said hopper and starting a new roll of bandage.

6. In a bandage winding machine, means to rotatably support a roll of fabric, a winding spindle, means to apply powdered material to said fabric as it is drawn downward by said winding spindle, an electric motor to rotate 10 said spindle, a rheostat for said motor, a wheel engaging and measuring the fabric as it is drawn downward, and means to increase the effective resistance of said rheostat on each revolution of said measuring wheel, whereby the 15 winding speed is reduced as the diameter of the bandage on said spindle is increased.

7. In a bandage winding machine, means to rotatably support a roll of fabric, a winding spindle, means to apply powdered material to 20 said fabric as it is drawn downward by said winding spindle, an electric motor to rotate said spindle, a rheostat for said motor, a wheel engaging and measuring the fabric as it is drawn downward, means to increase the effective 25 resistance of said rheostat on each revolution of said measuring wheel, whereby the winding speed is reduced as the diameter of the bandage on said spindle is increased, and means to stop the machine and simultaneously 30 reset the rheostat for high speed when a predetermined length of bandage has passed under the measuring wheel.

8. In a bandage winding machine, means to rotatably support a roll of fabric, means to draw 35 a piece of fabric through said machine, means to apply powdered material to said fabric as it is drawn through said machine, a measuring wheel engaged and rotated by direct contact with the fabric passing through said machine, 40 and means to stop the winding operation after a predetermined number of revolutions of said measuring wheel.

9. In a bandage winding machine, means to rotatably support a roll of fabric, means to draw 45 a piece of fabric through said machine, means to apply powdered material to said fabric as it is drawn through said machine, a measuring wheel engaged and rotated by direct contact with the fabric passing through said machine, 50 means to stop the winding operation after a predetermined number of revolutions of said measuring wheel, and means to sound an audible signal for each revolution of said wheel.

10. In a bandage winding machine, means to 55 draw bandage fabric through said machine, means including a hopper to supply powdered material to said bandage, means to heat the powdered material in said hopper, and heat-control means coacting with said winding means 60 and automatically effective to render said heating means inoperative when said winding means is inoperative.

11. A bandage winding machine comprising 65 means to draw a bandage through said machine, means to load said bandage with powdered material, and means to deposit additional material in spaced ridges on one side of said bandage, whereby the layers of wound bandage will be spaced apart by said ridges.

70 12. In a bandage winding machine, a vertically-disposed, glass supporting plate, a hopper in front of said plate, means to draw a piece of fabric downward between said plate and said hopper, and a doctor bar controlling the amount 75

of powder deposited on said fabric and guiding said fabric in contact with said plate.

13. In a bandage winding machine, a vertically-disposed, glass supporting plate, a hopper in front of said plate, means to draw a piece of fabric downward between said plate and said hopper, and a doctor bar to control the amount of powder deposited on said fabric and to guide said fabric in contact with said plate, said bar having spaced notches in its operative edge forming spaced parallel ridges of excess powder lengthwise of said fabric.

14. In a bandage winding machine, a vertically-disposed, glass supporting plate, a hopper in front of said plate, means to draw a piece of fabric downward between said plate and said hopper, a doctor bar controlling the amount of powder deposited on said fabric and guiding said fabric in contact with said plate, said bar having spaced notches in its operative edge forming spaced parallel ridges of excess powder lengthwise of said fabric, and a guide-roll for

said fabric having grooves spaced to correspond to said notches and clearing said ridges.

15. A bandage winding machine comprising a winding device, means to rotatably support a roll of fabric, said device and said means being substantially in vertical alignment and substantially spaced apart, means to apply powdered material to said fabric as it is drawn downward by said winding device, and a swinging curved plate yieldingly engaging the roll of bandage as it is wound and retarding displacement of powder loaded on said fabric.

16. In a bandage winding machine, a wiping roll comprising a substantially flat blade rotatably mounted and having alternate recessed and toothed edge portions.

17. In a bandage winding machine, a notched doctor bar, and a wiping roll comprising a substantially flat blade rotatably mounted and having double flat portions spaced to correspond to the notches in said doctor bar.

FRANK H. WASHBURN, JR.
